PREPARATION OF METHYLTRIMETHYLOL-METHANE

Merlin M. Brubaker, Wilmington, Del., and Ralph A. Jacobson, Landenberg, Pa., assignors to E. I. du Pont de Nemours & Company, Wilmington, Del., a corporation of Delaware

No Drawing. Application May 10, 1938,
Serial No. 207,012

1 Claim. (Cl. 260—635)

This invention relates to an improved method of preparing methyltrimethylolmethane and more particularly to an improved method for preparing this compound from formaldehyde and propionaldehyde.

An object of this invention is to provide an improved process of preparing methyltrimethylolmethane whereby good yields are obtainable. A more particular object is to provide an improved method for preparing this compound from propionaldehyde and formaldehyde, and for isolating the product in an effective manner from the reaction mixture. Other objects will be apparent from the ensuing description of the invention.

The above objects are accomplished by reacting propionaldehyde with aqueous formaldehyde in the presence of alkali and distilling the product with superheated steam in a vacuum, whereby the methyltrimethylolmethane is obtained in pure form and good yield. It is desirable, prior to the vacuum steam distillation, to subject the crude initial condensation product to one or more preliminary purification treatments, which are characterized hereinafter.

If a mixture of aqueous formaldehyde and propionaldehyde is slowly treated with solid caustic alkali, beginning at a controlled low temperature, e. g., 0° to 10° C., a colorless syrup is obtained containing a high yield of methyltrimethylolmethane. The reaction by which this compound is formed is illustrated by the following equation, sodium hydroxide representing the caustic alkali:

After production of the methyltrimethylolmethane-alkali hydroxide mixture in this manner, the isolation of this product presents a difficult problem. We have now found that this problem may be overcome by subjecting the mixture to vacuum distillation with superheated steam. The steam is suitably heated to 200 to 300° C., though temperatures outside this range are not precluded. In practice, it is desirable, before proceeding with the latter distillation, first to subject the crude reaction product to ordinary vacuum distillation in order to remove lower boiling impurities which are present, thereby leaving a mixture of alkali formate and methyltrimethylolmethane to be separated by the vacuum, 55

superheated steam distillation. This ordinary vacuum distillation is also desirably in turn preceded by treatment of the crude initial condensation product with the calculated amount of sulfuric acid, whereby the alkali formate is converted to alkali sulfate, a part of which separates and may be filtered off. This preliminary conversion of alkali formate to alkali sulfate, and the partial removal of the latter, is advantageous particularly with those types of stills where a large amount of alkali formate might offer obstruction to the passage of steam. The final mixture to be separated by the vacuum, superheated steam distillation, of course, consists in this instance of methyltrimethylolmethane and alkali sulfate rather than formate.

The above treatments prior to the vacuum superheated steam distillation, while they enable the process involving the latter distillation to be carried out with better results, are not absolutely essential, and, with or without them, the mentioned type of steam distillation enables the production of pure methyltrimethylolmethane in excellent yields, the difficultly removable alkali formate or sulfate, as the case may be, remaining as a residue in the still.

Commercial formalin (37% aqueous formaldehyde) is a convenient, satisfactory and economical source of formaldehyde, but paraformaldehyde or trioxymethylene may be used if desired. The caustic alkali may be used in solid form (sticks, flakes, or pellets) or as an aqueous solution. Any alkali metal hydroxide is suitable, sodium hydroxide being preferable from the standpoint of cost and potassium hydroxide from the standpoint of the greater solubility of the resulting potassium formate with attendant greater facility in the steam distillation.

In the preliminary purification step wherein 40 the crude reaction product is treated with sulfuric acid, the latter acid may be replaced by any other strong inorganic acid, such as hydrochloric, phosphoric or nitric acids. These acids, however, are in general less satisfactory than 45 sulfuric because the resulting salts are in general more soluble than sodium sulfate in the reaction medium. An acid which forms an insoluble or only partially soluble salt is preferred. The reaction is preferably begun at a relatively 50 low temperature, i. e., around 10° C., because shortly after addition of potassium or sodium hydroxide is started, a strong exothermic reaction takes place resulting in a sudden temperature rise. Although the temperature may rise to 60° or 70° C. without apparent harm as far as yields

are concerned, there is danger of loss of material and effective cooling is desirable in order to keep the reaction under control. Accordingly, we normally prefer at this stage to keep the temperature at about 30° C. or less.

The time for the initial reaction is largely governed by the rate of addition of the alkali and the rate is in turn governed by the effectiveness of the cooling system, but in general from 3 to 6 hours is required.

The excess water, formaldehyde and low boiling constituents of the reaction mixture can be removed by evaporation, distillation or by vacuum distillation, although we prefer to remove them by vacuum distillation since the operation can be accomplished in a shorter time and to a more complete degree. The residue left from this distillation is a mixture of alkali formate and methyltrimethylolmethane. For the separation of these two products the steam-distillation with superheated steam is best carried out at a temperature of about 250° C. and a vacuum of about 40 mm., though other pressures and temperatures may, of course, be used. The pressure and temperature, as those skilled in the art will understand, must be co-adjusted. For example, if the pressure is in the range of 20 to 25 mm., the temperature can be reduced to 225° C. with equally desirable results.

For the reaction itself, any type of vessel provided with a stirrer and a means of cooling can be utilized. For the distillation, any of the usual types of equipment for vacuum distillation can be employed provided that means for uniformly heating the kettle and for introducing superheated steam are provided. However, since large amounts of alkali formate are left as a residue, the most satisfactory type of still is one in which the mixture of alkali formate and methyltrimethylolmethane remaining after distillation of the more volatile constituents is fed onto hot rolls under reduced pressures. The methyltrimethylolmethane is thereby volatilized by a flash distillation while the alkali formate remains on the rolls and is continually removed therefrom by a scraping device.

The following examples, in which parts are by weight, illustrate more exactly how the invention is practiced.

Example I

A mixture of 12,200 parts of 37% aqueous formaldehyde solution and 2900 parts of propionaldehyde is cooled to 10° C. in a kettle provided with a stirrer and a reflux condenser and provided with a jacket for circulation of a cooling liquid. To this solution is slowly added 2000 parts of solid sodium hydroxide while the temperature is maintained below 30° C. This operation requires about 6 hours. The mixture is then submitted to vacuum distillation at about 60 mm. pressure, while steam is slowly passed into the mixture. By this procedure, water, unreacted formaldehyde and small amounts of volatile by-products are distilled out leaving a mixture of 65 sodium formate and methyltrimethylolmethane

in the still pot. The pot is then heated to 250° C. by circulating hot oil through the jacket formerly used for cooling, and superheated steam is passed into the mixture of sodium formate and methyl trimethylolmethane, while maintaining a vacuum on the system of 40 to 50 mm. By this procedure the methyltrimethylolmethane is volatilized, passes through a short heated pipe and collects in a series of two condensing vessels surrounded by water, the temperature of which can be regulated. Most of the methyltrimethylolmethane condenses in the first condensing vessel, the remainder being stopped by the second condenser. A total of 4770 parts (79.5%) of methyltrimethylolmethane is obtained. This product is sufficiently pure for most purposes but it may be crystallized readily from acetone to give analytically pure crystals melting at 198-199° C. The sodium formate remains in the still pot.

Example II

A mixture of 12,200 parts of 37% aqueous formaldehyde solution and 2900 parts of propionaldehyde is treated slowly with 2000 parts of solid sodium hydroxide as described in Example I. The reaction mixture is then treated with dilute sulfuric acid containing 2250 parts of actual sulfuric acid. The latter converts the sodium formate in the mixture into sodium sulfate which, being less soluble in the solution than sodium formate, separates in part from the solution. The sodium sulfate which precipitates is filtered off and the filtrate then distilled as in Example I, the easily volatile constituents being first distilled by gentle heating in a vacuum and the methyltrimethylolmethane being finally volatilized by heating the still pot to 250° C. and passing in superheated steam. The methyltrimethylolmethane is obtained in the condensers as in Example I and amounts to 4914 parts or 81.7% of the theoretical.

Although acetone has been described in the examples as the preferred solvent for recrystallization of the methyltrimethylolmethane, other ketone-type solvents, such as methyl ethyl ketone are also satisfactory and may be substituted for the acetone. Ester-type solvents, such as butyl acetate are also suitable.

Various changes may be made in the details and operation of the present invention without departing therefrom or sacrificing any of the advantages thereof.

We claim:

In a process for producing methyltrimethylolmethane by reaction of formaldehyde and propionaldehyde, the step which comprises carrying out the reaction in the presence of an alkali metal hydroxide, converting the alkali formate in the reaction product to alkali sulfate, removing the sulfate which separates, and removing by vacuum distillation volatile impurities boiling lower than methyltrimethylolmethane, and isolating methyltrimethylolmethane from the residue by distilling in vacuo with superheated steam.
